CLAIM

The ornamental design for a candy, as shown and described.

DESCRIPTION

FIG. 1 is a perspective view of a candy showing our new design, according to a first embodiment;

FIG. 2 is a top view of the design shown in FIG. 1;

FIG. 3 is a left view of the design shown in FIG. 1;

FIG. 4 is a right view of the design shown in FIG. 1;

FIG. 5 is a rear view of the design shown in FIG. 1;

FIG. 6 is a front view of the design shown in FIG. 1; and,

FIG. 7 is a bottom view of the design shown in FIG. 1.

The “Dove” indicia forming part of the claimed design is a registered trademark of MARS, Incorporated.
